C. M. GOLDINGER

UNCOUPLING LEVER

Original Filed June 15, 1921

Patented May 3, 1927.

1,626,929

UNITED STATES PATENT OFFICE.

CARL M. GOLDINGER, OF TARENTUM, PENNSYLVANIA, ASSIGNOR TO WALTER P. MURPHY, OF CHICAGO, ILLINOIS.

UNCOUPLING LEVER.

Application filed June 15, 1921, Serial No. 477,767. Renewed October 1, 1926.

This invention relates to uncoupling devices for car couplers generally but more particularly to such devices for locomotives in which use it is highly desirable that the device may be operable from both sides of the locomotive.

The object of this invention is to provide an uncoupling device which may be operated from either side of the car and of such construction that the operating handle will not project forward from the end of the car when the lock pin of the coupler is in lock set position, means being provided to permit the handle to return to its normal substantially vertical position against the end of the car.

In some types of uncoupling devices the operating handle remains in its raised position when the lock pin is in lock set position, which in the case of use on a locomotive is very dangerous inasmuch as operators in stepping from the foot board usually found on the front end of locomotives, are liable to have their clothing caught in such out-standing handle whereby they may be thrown on the track and injured. Another objection to this type of device, formerly in use, is that frequently there are several persons on the foot board, in which case an operator is likely to be thrown off the foot board by the opposite handle of the device, when the device is operated from the other side of the car. These conditions make it desirable to provide an uncoupling device which may be operated from either side of the car without disturbing the normal vertical position of the handle on the other side of the car, and further, to provide means whereby the handle operated may return to its normal substantially vertical position, without disturbing the lock set position of the lock pin.

This invention consists of two operating levers separately mounted on a car upon opposite sides of the coupler, for independent operation and each provided with a depending handle at its outer end normally resting against the end structure of the car, and a crank at the inner end of each lever extending forwardly from the car and substantially at right angles to the handles, a rigid U bar link flexibly connected to the lock pin of the coupler at its lower end and vertically slidably connected at its upper end with said cranks whereby all service

movements of the coupler are permitted without imposing strain upon the levers, and whereby the levers may be independently operated and whereby the operated lever may return to its normal position without disturbing the lock set position of the coupler pin.

In the drawings—

Figure 1 is a top plan view of the end structure of a car with this invention in operative position thereon.

Figure 2 is a front elevation of Figure 1.

Figure 3 is a side elevation of Figure 1, the end structure being partly in section.

The reference numeral 1 designates the end structure of a car. It will be understood that the term "car" includes locomotives. Suitably secured to the end structure are side brackets 2, 3 and a double center bracket 4, said brackets being provided with filler blocks 5 and cotter pins 6, which lock secure the blocks and operating levers 7, 8 in said brackets; the levers being revolvably mounted.

The levers 7, 8 are provided with operating handles 9, 10 at their outer ends which, when in normal position depend vertically against the end structure. The inner ends of the levers are provided with cranks 11, 12 projecting forwardly from the end structure and substantially at right angles to the handles 9, 10, and terminate at their free ends in eyes 12, 13 positioned in a horizontal plane.

The cranks 11 and 12 are flexibly connected with the pin 14 of the coupler 15 by a rigid link which comprises a single bar bent to a substantially U shape thereby forming vertical arms 16, and a bottom connecting member 17, the upper end portion of each arm being rebent forwardly to form a downwardly open hook 18, 19.

The cranks, connecting link, and coupling pin are so operatively connected that they cannot be disconnected without first removing the levers 7 and 8 from their brackets.

In assembling the U shaped connecting link is passed through the eye of the lock pin 14 and then placed in a vertical position, then the hooks 18, 19 are passed through the eyes 12, 13 of the cranks and the levers are then revolvably secured in the brackets when the parts assume their normal position shown in Figure 3; the bottom member 17 being flexibly and loosely mounted in the

eye of the coupler pin, while the arms 16 of the connecting link are loosely mounted in the eyes 12, 13 of the cranks 11, 12 and free to move vertically relatively to said eyes, 5 whereby the link is free to move with the coupler in all service movements without imposing strain on the operating levers and their cranks.

It will be readily seen from the drawings 10 that the coupler pin may be operated and moved to lock set position by either lever 7, 8, without disturbing the normal position of the other lever, and that the lever which has been operated may return to its normal 15 position without disturbing the lock set position of the coupler pin.

The parts are so proportioned that there is no liability of their failing to properly function.

20 What is claimed is:

1. In an uncoupling device for car couplers the combination with a car coupler having an automatic lock pin provided with an eye, of a substantially U shaped rigid lock 25 pin lifting link loosely journalled at its bottom in the eye of the pin, and forwardly extending open bend portions at the top of each leg of the link, and two independently mounted levers, a flexible operative connection 30 between each of said levers and each leg of the link, whereby the link and pin may be raised by either lever independently and without disturbing the normal position of the other lever, and whereby the lever operated 35 may return to normal position without disturbing the lock set position of the lock pin.

2. In an uncoupling device for car couplers having an automatic lock pin provided with an eye, the combination of a pair 40 of operating levers mounted on a car for independent operation, a crank extending forwardly from the inner end of each of the levers and a handle at the outer end of each 45 lever substantially at right angles to the crank, an eye at the outer end of each crank, a substantially U shaped rigid pin lifting link the legs of which terminate at their upper ends in an open return bend disposed forwardly of the leg, the width of 50 bend being greater than the inside diameter of the eyes on said cranks, in which said legs of the link are loosely positioned and

vertically movable, the U shaped link being loosely journalled bodily in the eye of the 55 lock pin.

3. In an uncoupling device for car couplers, the combination with a car coupler having an automatic lock pin provided with an eye, of a substantially U shaped rigid lock 60 pin lifting link loosely journalled at its bottom in the eye of the pin, a stop at the upper end of each leg of said link, and two levers mounted for independent action, a flexible operative connection between each 65 of said levers and each leg of the said link, whereby the link and pin may be raised by either lever and without disturbing the normal position of the other lever, and whereby the operated lever may return to normal po- 70 sition without disturbing the lock set position of the lock pin.

4. In a release rigging for car couplers having a lock pin, a rigid pin lifting link substantially U shaped, each leg of which 75 terminates at its upper end in a normally open hook disposed at a right angle to the bottom of the link, the bottom member of the link being constructed to be journalled in the eye of the coupler lock pin, said legs 80 being designed for direct attachment to a coupler pin operating rod and at the same time be free to move vertically relatively to said rod.

5. In a release rigging, the combination 85 with the lock pin of a car coupler, of a pair of independently mounted operating rods, a lever on the inner end of each rod extending substantially over the coupler and terminating in a vertically disposed eye, a rigid 90 substantially U shaped link each leg of which terminates at its upper end in an open hook, each leg of said link being vertically slidably mounted in the vertical eye of its respective lever, and the link being flexibly 95 connected at its lower end to the said pin.

6. In a release rigging for car couplers having a lock pin with an eye, a rigid sub- 100 stantially U-shaped pin lifting link, each leg of which has restricted slidable engagement through an eye of a coupler pin operating rod, the bottom of said link being journaled in the eye of the lock pin.

In testimony whereof I affix my signature.

CARL M. GOLDINGER.
